UNITED STATES PATENT OFFICE.

FRANCIS A. J. FITZ GERALD, OF NIAGARA FALLS, NEW YORK, AND JAMES KELLEHER, OF CHIPIAWA, ONTARIO, CANADA, ASSIGNEES TO HARPER ELECTRIC FURNACE CORPORATION, A CORPORATION OF NEW YORK.

ELECTRIC FURNACE TERMINAL.

Original application filed June 10, 1925, Serial No. 36,086. Divided and this application filed March 26, 1926. Serial No. 97,500.

This invention relates to furnaces adapted to be heated by electric resistors. In its preferred embodiment it relates to a furnace of this character wherein the resistor is located in a chamber which is sealed from the outside atmosphere so as to prevent access of air to the heated resistor.

Among the objects of our invention is to provide means whereby current may be conducted through the wall of the chamber to the resistor without danger of gas leakage between the chamber and the outside atmosphere. A further object is to provide an improved resistor terminal which extends through the wall of the chamber and is sealed thereto. A further object is to provide an improved resistor terminal which is formed and sealed in the wall of the resistor chamber, in such a manner, that loss of heat from the chamber by conduction out through the terminal is reduced to a minimum. A further object is to provide an improved resistor terminal which is simple and economical in construction, strong and durable, and which may be employed as a support for the resistor. A further object is to provide a resistor terminal having an improved means for cooling the same so as to prevent injury due to overheating.

Other objects and advantages of our invention will appear from the following description taken in connection with the accompanying drawing, wherein

Fig. 1 is a detailed elevation, partly in section, showing a portion of the walls of the heating chamber of a furnace, a portion of a resistor located therein and a conducting terminal secured to the resistor and passing through a wall of the chamber.

Fig. 2 is a detailed elevation of a portion of the structure shown in Fig. 1, showing a slight modification.

Fig. 3 is a sectional view taken on the line 3-3 of Fig. 2.

Fig. 4 is a view similar to Fig. 2, but showing a still further modification.

Fig. 5 is a sectional view taken on the line 5-5 of Fig. 4.

Fig. 6 is a side elevation of another form

of terminal showing an improved means of securing the resistor thereto.

Fig. 7 is a top plan view of the structure shown in Fig. 6.

Fig. 8 is an elevation of the outer end of the terminal shown in Fig. 7.

Fig. 9 is a section taken on the line 9-9 of Fig. 6 showing a portion of the resistor in elevation.

In electric furnaces of the resistance type it is often desirable to use a terminal having different cross section and shape through its length. These terminals are often formed of Acheson graphite or some other form of carbon. When the portion of the terminal inside the furnace has to be larger due to mechanical necessity, than actually required for carrying current, the cost of making these terminals out of large blocks of graphite becomes great. The heat loss is also greater through a large heavy terminal. In the forms of terminals shown in Figs. 1 to 5, we have provided an improved construction whereby the terminals may be made of two or more differently shaped pieces, such pieces giving the desired mechanical design, good electrical properties, and permitting easy water-cooling facilities, which are generally necessary to prevent oxidation of the terminal.

Referring to Fig. 1, the resistor 13 is adapted to be supported on a resistor-carrying block 75 of squared cross section, which in turn is connected, both mechanically and electrically, to the cylindrical portion 76 of the terminal by means of a threaded tapered extension 77 formed on the cylindrical portion 76 and which fits into a threaded recess in the resistor-carrying block 75. This joint, although mechanically and electrically good, is still a poor conductor of heat and serves to prevent considerable heat loss from the resistor 13. This joint, may, if desired, be formed as shown in Figs. 2 and 3, wherein the cylindrical member 76 carries a tapered lug 80 adapted to be seated in a recess in the resistor-carrying block, and the two portions held together with carbonaceous half-pins 81. In case it is desired to form the

terminal portion which passes through the furnace wall of rectangular section, it may be formed as shown at 82 in Figs. 4 and 5, and secured to the angular recess 83 by the half-pins 81.

In order to prevent the outer portion of the terminal from burning, the coil of pipe 85 is wound around the portion 76 as shown in Fig. 1, and lead or other easily cast metal is poured around it so as to make good heating contact between portion 76 and the coil 85. Water enters this coil at 88 and leaves it at 89. Electrical connection with the portion 76 may be made at 90 by some suitable means. The lead surrounding the coil 85 may have its outer surface cast to any shape suitable to be built into the refractory brick-work of the furnace.

It will be seen how readily this form of construction may be suited to fit different furnaces and the shapes employed may be altered without departing from the general scope of the invention.

If the cross section of the copper pipe 85 is made sufficiently large, the current required by the resistor 13 may be conducted through pipes 85 to the terminal portion 76. This permits an even shorter terminal and also allows the whole to be bedded solidly in the brickwork and eliminates the necessity of the electrical connection 90.

In Figs. 6 to 9, we have shown another form of terminal which is provided with an improved means for securing the resistor thereto and which is further provided with cooling means and means whereby an inert gas may be supplied to the resistor chamber through the body of the terminal. This terminal consists of Acheson graphite or some other carbonaceous material and is provided near its inner end with an inner pocket or space 100 into which the end of the resistor 13 fits. A coil of pipe 102 designed to carry water or other cooling medium is seated in a deep slot or cavity 103 cut or moulded into the terminal. The cooling medium circulated in the pipe 102 serves to keep that part of the terminal which is subjected to the oxidizing effects of gases or material below a temperature where oxidation occurs. That part of the slot 103 which is not filled with the pipe is packed with some good heat-conducting material such as graphite powder, or it may be filled with metal such as lead, etc.

The long narrow passage 105 is drilled, built or moulded into the terminal and has an outlet 106 which, when the terminal is built into the kiln, is inside the chamber on which the resistor is located and an inlet 107 opening outside of the kiln. This passage is employed to supply an inert gas or vapor to the resistor chamber. The passage 105 may, if desired, be lined with some hard inert substance such as porcelain, glass or other

material to prevent erosion of the terminal by the rapidly moving gases.

As stated, the resistor 13 is seated in the recess or pocket 100 of the terminal, and in order to permit the placing and removing of this resistor in an easy manner, we provide a removable plate 110 of the same material as the terminal, which is adapted to be seated in bevelled or dovetailed grooves formed in the side walls of the recess 100. As shown in Fig. 9, a wall 111 is left at one side of the recess 100.

When it is desired to place a new resistor in the terminal, plate 110 is removed, the resistor dropped into the recess 100, and the space between the end of the resistor and the terminal packed with some such material as graphite, so as to make good electrical contact. In placing this packing, the web or wall 111 is of great help and the web also helps to reinforce the terminal at that part of the recess. When the sides are packed, the plate 110 is slipped into position and the space 112, Fig. 9, is packed in a similar manner with graphite.

This application is a division of Fitz-Gerald and Kellcher application, Serial No. 36,086, filed June 10, 1925, for tunnel kiln.

We claim:

1. An electric terminal for use in electric resistor furnaces, comprising a portion formed to extend through and be sealed into the wall of said furnace, and a second portion of different form, adapted to receive and providing a circuit connection with one end of a resistor, said portions being joined together by a connection of high electrical and low heat conductivity.

2. An electric terminal for use in electric resistor furnaces, comprising a portion formed to extend through and be sealed into the wall of said furnace, and a second portion of different form, adapted to receive and providing a circuit connection with one end of a resistor, said portions being joined together by a carbonaceous connection of high electrical and low heat conductivity.

3. An electric furnace having a wall, an electric terminal sealed through said wall, said terminal having a detachable joint of high electrical and low heat conductivity located at approximately the inner face of said wall, and fluid circulating means extending within said wall to a point beyond the centre thereof for cooling a portion of the terminal therein.

4. A carbonaceous electric terminal for use in electric resistor furnaces comprising a cylindrical portion adapted to be sealed through the wall of said furnace, a rectangular portion adapted to support one end of a resistor, said portions being detachably joined by a connection of high electrical and low heat conductivity.

5. A terminal for electric resistor fur-

- naces comprising a cylindrical carbonaceous member adapted to be sealed into the wall of said furnace, a rectangular carbonaceous member joined to said first-named member by a screw connection of carbonaceous material, said second-named member being located inside the furnace and being adapted to support and form electrical connection with one end of a heating resistor.
10. 6. A terminal for electric resistor furnaces comprising a cylindrical carbonaceous member adapted to be sealed into the wall of said furnace and formed at its inner end with a tapered projection, a rectangular carbonaceous member adapted to support and form electrical connection with one end of a heating resistor and formed with a tapered recess adapted to receive the tapered projection of said cylindrical member, and
- 15 20 carbonaceous pins securing said members together.
7. An electric furnace having a wall, a terminal passing through said wall, a pipe for conveying cooling medium surrounding said terminal in said wall, and fusible metal sealing said terminal and pipe into said wall.
- 25 30 35 8. An electric furnace having a wall, a terminal comprising a cylindrical carbonaceous member passing through said wall, a coil of pipe for conveying cooling medium surrounding said member in said wall, and fusible metal sealing said member and pipe into said wall whereby electric current may be supplied to said terminal through said pipe.
9. A terminal adapted to extend through
- the wall of an electric furnace comprising a carbonaceous block having its inner end connected to a resistor and a deep slot opening at the outer end of said block, and a pipe adapted to convey a cooling medium located in said slot to cool said block.
10. A terminal adapted to extend through the wall of an electric furnace comprising a carbonaceous block having a deep slot opening at the outer end of said block, a pipe adapted to convey cooling medium located in said slot, and fusible metal filling the space between said pipe and the walls of said slot.
11. In an electric furnace having a wall, a terminal formed of a carbonaceous block extending through said wall and formed near its inner end with a recess opening upwardly and at one side of said block, a carbonaceous resistor having one end seated in said recess and carbonaceous packing between said end and the walls of said recess.
12. In an electric furnace having a wall, a terminal formed of a carbonaceous block extending through said wall and formed near its inner end with a recess opening upwardly and at one side of said block a carbonaceous resistor having one end seated in said recess, carbonaceous packing between said end and the walls of said recess, a carbonaceous plate fitted into and closing the top of said recess, and carbonaceous packing between said end of the resistor and said plate.
